UNITED STATES PATENT OFFICE

HENRY L. DOHERTY, OF NEW YORK, N. Y.

METHOD AND APPARATUS FOR DISTILLING SOLID CARBONACEOUS MATERIAL

Application filed May 8, 1925. Serial No. 28,866.

This invention relates to the control of fuel distillation and more particularly to a method of and apparatus for controlling the distillation of fuel by direct heat transfer with 5 hot non-combustion-supporting gases.

In operating gas generators and carbonizing units of the shaft type wherein raw fuel is introduced into the top of the shaft and is gradually distilled or carbonized during its 10 downward passage through the upper part of the shaft by an upwardly flowing current of hot non-combustion-supporting gas, difficulty is often encountered in securing a uniform distillation and/or gasification of the 15 fuel during its passage through the shaft. One of the principal causes of this non-uniform distillation of the fuel is that the heating gas seeks out and follows paths of least resistance in its upward passage through the 20 shaft, and often develops "channels" through the fuel bed. Once a "channel" is formed more and more of the gas will enter it because the fuel in the "channel" will be more rapidly and completely carbonized by the larger volume 25 of gas passing therethrough, and the coke or carbonized fuel in the "channel" will thereafter offer much less resistance to the passage of the gas than the raw and partially carbonized or "plastic" fuel along the "walls" 30 of the "channel". This "channeling" of the fuel bed by the hot gas distilling medium occurs most frequently along the inner walls of the shell. Usually when "channels" are developed the capacity of the furnace is lowered 35 and some of the fuel passes through the shaft without undergoing complete distillation and/or combustion.

The shaft retort or generators commonly used for fuel distillation by hot gases are 40 generally equipped with a single fuel charging inlet at the top of the shaft and a single gas outlet leading off from one side of the upper wall. In a retort of this type the "channeling" tendency of the hot gas distilling medium is usually very marked. The gas naturally seeks out the easiest path toward the gas off-take, and after it has once opened a "channel" through the fuel bed of such a retort, it is almost impossible to 45 block the channel or to force any of the gas

through that portion of the fuel bed which lies outside the channel. Moreover, in shaft retorts, of this type, especially when the gas is removed under a vacuum, the "channels" are most often developed through the fuel 55 along that portion of the wall which lies immediately below the single gas offtake, where the suction created by the outgoing gas is strongest and where raw fuel is choke the channel can be introduced only with the greatest difficulty from the centrally located charging inlet.

The primary object of the present invention is to provide a method and apparatus by which solid volatile-containing carbonaceous 65 fuel may be distilled uniformly by direct heat transfer with a current of hot non-combustion-supporting gas.

With this object in view one feature of the invention contemplates distributing a 70 current of the heating gas uniformly through a bed of the said fuel advancing through a shaft retort and passing the gas in uniform or variable concentrations countercurrently throughout the whole upper cross section of 75 the fuel bed.

Another object of the invention is to provide a method of and apparatus for controlling the distillation of said volatile-containing carbonaceous fuel in operations where 80 hot non-combustion-supporting gas is used as the distilling medium.

To accomplish this object another feature of the invention contemplates distilling a bed of said fuel in a shaft retort by a current of 85 hot gas passed upwardly through the fuel and removed selectively from all or any portion of the upper cross section of the fuel bed.

Another feature of the invention contemplates adding said volatile-containing carbonaceous fuel periodically to substantially 90 the whole or any portion of the upper cross section of a bed of said fuel undergoing distillation by direct heat transfer with a current of hot non-combustion-supporting gas.

With these and other objects and features in view, the invention consists essentially in the method of and apparatus for controlling 95 distillation of solid volatile-containing car-

bonaceous fuel hereinafter described and particularly defined in the claims.

The various features of the invention are illustrated in the accompanying drawings, in which—

5 Fig. 1 is a view in sectional elevation of the upper part of a shaft retort equipped with a multiple gas offtake and fuel charging device of the type embodying the preferred form of the invention;

10 Fig. 2 is a plan view showing the multiple gas offtake and fuel charging device partly in section taken on the line 2—2 of Fig. 1; and

15 Fig. 3 is a vertical cross section through a shaft generator equipped with a modified form of the multiple gas offtake and fuel charging device shown in Figs. 1 and 2 and also equipped with a fuel discharge mechanism.

20 The method of controlling distillation of solid volatile-containing carbonaceous fuel constituting the preferred form of the present invention as carried out in the apparatus illustrated in the drawings consists in introducing said fuel, such for example as wood, lignite or bituminous coal, oil shale, etc., preferably in admixture with a small proportion of coke or other non-volatile-containing heat and abrasion resistant refractory material, periodically from a hopper 10 into the top of a shaft retort or generator 12 through any one or more or all of a number of charging gates 14 and necks 16, and through a plurality of depending ducts or chambers 18

35 which open into the shaft at their lower ends. Each of the chambers 18 preferably has the same cross sectional area as each of the others, and the chambers are preferably arranged in rows to form a partitioned charging box

40 which occupies substantially the whole upper cross section of the shaft. The volatile-containing fuel is supported in and gradually passed downwardly through the shaft in a column and as it advances through the upper portion 19 it is gradually heated and distilled by a current of hot gases rising upwardly through the shaft toward a number of gas offtakes 20. When the shaft is being used as a gas generator, the hot gas for distilling or carbonizing the fuel may be generated by introducing combustion supporting gases through a conduit 22 and a blast nostril 24 into that portion of the fuel bed lying im-

45 mediately adjacent rack back or circumferential arch 26. When the shaft is being used solely as a distilling or carbonizing chamber the hot gases required for distilling or carbonizing the fuel may be introduced into the shaft from some outside source through nostril 24. In any case a sufficiently large volume of gas must be passed through the upper zone of the fuel bed and the gas must have a

50 temperature sufficiently high so that all the fuel will be distilled to the desired degree by

sensible heat given up by the gas during its passage upwardly through the shaft.

To counterbalance the tendency of the heating gas to follow or develop "channels" through the bed of fuel, each of the plurality of gas offtakes 20 is equipped with a valve 28. Whenever "channels" are developed in the fuel the valves of these offtakes which are directly above the channel and through which the larger volumes of gas are passing out of the generator may be either partially or completely closed in order to force the upwardly flowing gas to leave the "channel" and pass through those sections of the fuel bed which have been deprived of the necessary volume of gas to complete distillation during the period in which the "channel" was developing. Thus when one or more, "channels" is formed along the inner walls of the shaft, the large proportions of the gas which are passing off through those offtakes leading from the peripheral section of the shaft at points immediately above these "channels" may soon be detected by means of meters or other indicating devices which are preferably connected to each offtake (not shown). By closing or partially closing the valves in these particular offtakes some or all of this gas will be forced to travel transversely through the fuel bed toward the axially located offtake and toward the other peripheral offtakes. In general when the combustion supporting gases or the heating gases are introduced through an inlet in the periphery of the shell, as through conduit 22 in the design illustrated in the drawings, a uniform distillation of the fuel may be best secured by keeping the valves of the offtakes leading from the upper peripheral section of the shaft partly closed, and by allowing the greatest proportion of the gas to pass out through the axially located offtakes, so as to counterbalance the tendency of the gas to develop "channels" along the inner wall of the shaft between the peripheral gas inlet and the peripheral gas offtakes.

55 All of the gas offtakes 20 are connected to extension 30, equipped with valves 32, of a common manifold 34, and the mixture of heating gas and volatile products of fuel distillation which is removed from the top of the shaft through the several offtakes passes through the manifold into a foul gas main 36, and is thence preferably conducted through condensing scrubbing and purifying equipment (not shown) to a storage holder or to service mains.

60 The charging gates 14 may be operated in the same or on alternate cycles. As each charging gate makes a revolution it introduces a proportionate amount of solid volatile-containing carbonaceous fuel into the top of the generator through its corresponding duct 18. If for instance it is found that fuel passing downwardly through the periph-

eral portions of the cross section of the heating and distilling zone 19 is distilled more rapidly or more completely by the rising current of hot gases than fuel passing through the axial section of zone 19, fuel 5 may be added more frequently to these peripheral sections than to those axial sections in which the distillation takes place more slowly, and also the fuel in the peripheral sections of the column may be more rapidly 10 advanced through the shaft to counterbalance the preferential distilling tendencies of the heating gases. Thus in Fig. 3 of the accompanying drawings there is shown a shaft having ducts 18 arranged in an annular concentric form over its entire upper surface to allow for the separate and selective charging and distillation treatment of two or more distinct types of solid volatile-containing carbonaceous fuel, if so desired. There is also 15 shown in Fig. 3 one type of fuel-supporting and discharging mechanism 38 designed to serve as a positive support for a column of fuel in the shaft and operable to advance fuel 20 at a controlled rate through the axial and peripheral sections of the shaft in the manner above referred to. Essentially the discharge mechanism 38 illustrated in Fig. 3 comprises three distinct stationary and movable elements 25 mounted in the lower portion of the shaft in such a way as to completely fill the lower cross section of the shaft and thereby afford a positive support for a column of fuel therein. The first element of the discharge 30 mechanism 38 illustrated comprises an upright stationary cone-shaped member 40 mounted in the axial portion of the shaft at a vertically spaced distance above the second element which in turn comprises a movable 35 annular ring or plough member 42 supported by and arranged to oscillate back and forth 40 across the surface of an annular stationary plate 44 comprising the lower and third element of the mechanism 38. The cone 40 and the plate 44 together serve as a positive support 45 for a charge of fuel in the shaft, and the oscillating movement of the ring 42 serves to discharge fuel from the surface of plate 44 through a central opening 46 lying beneath the cone 40 and through an annular 50 opening 48 lying between the periphery of the plate 44 and the inner walls of the shaft. The rate at which ring 42 is oscillated is governed in accordance with the rate at which it 55 is desired to advance fuel downwardly through the axial and peripheral portions of the shaft. Means, illustrated as hydraulic reciprocating engines 50 mounted outside the shaft and connected by connecting rods 52 60 to the ring 42, serve to impart an oscillatory motion to the ring 42 and to control the rate and path of travel of the ring in accordance with the rate at which it is desired to advance fuel downwardly through the axial and peripheral 65 portions of the column of fuel supported in the shaft. For a more complete description of the fuel supporting and discharging mechanism 38 reference is hereby made to my Patent 1,426,159, dated August 15, 1922. The valves 32 in each of the extension or 70 withdrawal pipes 30 of the manifold 34 provide additional means for governing the selective removal of gas from any three or more of the larger portions of the cross section of the shaft. Thus in addition to providing for a selective removal of gas through each one or more of the chambers 18 and the outlet conduits 20 by valves 28, the valves 32 provide a separate control for the selective removal of gas through each row or series 75 of chambers 18 and conduits 20. The provisions for selective gas removal from the shaft and for preferential control of the volume of solid volatile-containing carbonaceous fuel added to each section of the 80 shaft makes the method and apparatus of the present invention particularly suitable for the distillation treatment of two or more distinct kinds of said fuel simultaneously in one shaft unit. Thus, one kind of fuel may 85 be charged through one row of charging necks and distilled during its downward passage through the section of the shaft lying immediately beneath these charging necks by an upwardly flowing current of hot gases, 90 the gases evolved therefrom being removed through the row of outlet conduits which lead off from the top of the shaft adjacent the corresponding charging necks, while another row of charging necks, another section 95 of the shaft, and another row of gas outlets 100 may be used simultaneously in respectively charging, distilling and removing gas distilled from another kind of fuel. Likewise, alternate charging necks and chambers 18 105 may be used for introducing two or more distinct kinds of fuel into the top of the shaft in alternate vertical layers. For example coal and coke may be introduced into the shaft through alternate charging doors and chambers, being thus directed through the shaft 110 in alternate vertical layers, such for instance as a central core of coke surrounded by annular cylinders or coal and coke of an ever increasing diameter. When such a procedure 115 is contemplated the fuel hopper 10 must of course be partitioned into separate compartments for each of the several kinds of fuel to be treated.

According to the preferred method of operation, the fuel to be distilled, especially when it is a bituminous coal, is mixed before its introduction into the shaft with about twenty to thirty per cent by volume of coke or other refractory material. The chief object of charging this refractory in admixture with the fuel is to provide an open and porous bed in the shaft through which the hot gas distilling medium can distribute itself in substantially uniform concentrations, without 120 125 130

being obstructed by impenetrable layers of fuel in the "plastic" stage of thermal decomposition.

As previously indicated, one advantage of having a plurality of gas outlets distributed over substantially the full top area of the shaft is that with this arrangement there is substantially no preferential suction created by the gas passing out through any one outlet and the hot gas distilling medium will be drawn through each section of the fuel bed at substantially the same rate as through each of the others and therefore will not be so apt to open and develop "channels" through any one section of the bed as it would if there were only one offtake. Another advantage of this arrangement is that if "channels" do form, they may be quickly choked up or obliterated by a preferential charging of the fuel into the top of the bed above the outlet of the "channel", and by a selective removal of the gas distilling medium through other outlets than those leading off directly above the outlet of the "channel." Another advantage is that if for instance, fuel falls more rapidly through the outer zones or peripheral sections of the shaft, it is possible to charge fuel more rapidly into those zones, and if any particular zone of the fuel charge gives up one kind of gas as distinguished from another kind of gas, these different forms of gas can be removed separately from the top of the shaft.

It is not intended that the invention be limited to the particular arrangement of apparatus illustrated in the drawings. The combination fuel charging and gas removal chambers 18, a plurality of which make up the charging box at the top of the shaft, may have a rectangular, circular or elliptical cross section, and they may be arranged within the partition and charging box in concentric circles, squares or other shaped divisions. In the preferred arrangement, however, each chamber 18 is equipped with one or more individual gas offtake conduits having individual valves and one or more individual fuel charging necks having individual charging gates so that the chamber can be used simultaneously as an outlet for the gas evolved in the shaft and as an inlet for the fuel to be distilled. By this arrangement the sensible heat of the hot gas distilling medium and of the volatile products distilled from the fuel can be most effectively utilized in preheating raw fuel.

The term "solid volatile-containing carbonaceous" is used in the claims as a broad generic term to cover combustible carbonaceous or bituminous material such as wood, lignite or bituminous coal, oil shale, peat, and like solid carbonaceous materials having volatile constituents separable therefrom by distillation at an elevated temperature.

25 In order to secure large yields of products

of high quality from the fuel carbonization, the heating gas employed is preferably combustible gas, i. e., one containing little or no uncombined oxygen or air. Accordingly in the specification and claims this heating gas has been described as a "non-combustion supporting gas" to distinguish it from blast air or similar gases used in the generation of combustible gas.

The preferred form of the invention having been thus described what is claimed as new is:

1. A method of controlling distillation of solid volatile-containing carbonaceous fuel which comprises passing said fuel downwardly in a column through a shaft retort, passing a current of hot non-combustion-supporting gas upwardly through the fuel column to distil the fuel by heat transfer therewith, and removing the mixture of gas distilling medium and volatile products evolved from any portion of the fuel selectively from the top of the fuel column so as to force the gas distilling medium to distribute itself in uniform concentrations through each cross section of the fuel column during its upward passage therethrough.

2. A method of controlling distillation of solid, volatile containing carbonaceous fuel, which comprises separately adding portions of said solid fuel periodically and selectively to the various parts of the upper cross section of a column of fuel passing downwardly through a shaft retort and adding said fuel to each of said various parts at such a rate that the fuel in the column will be distilled to a uniform degree during its passage through the shaft by direct heat transfer with an upwardly flowing current of hot non-combustion-supporting gas.

3. A method of controlling distillation of solid volatile-containing carbonaceous fuel which comprises introducing said fuel periodically through each one of a plurality of charging gates into the top of a shaft retort, passing the fuel downwardly in a column through the shaft, introducing a hot non-combustion-supporting gas into the lower portion of the column, passing the hot gas upwardly through the column in direct heat transferring relationship with the fuel to distil the fuel and drive off its volatile components, removing the mixture of gas distilling medium and volatile components of the fuel selectively through one or more of a plurality of gas offtakes at the top of the shaft, and controlling the addition of said fuel to and the removal of said gas from each portion of the upper cross section of the shaft to distil the fuel in each cross section of the column to a uniform degree during its passage through the shaft.

4. A method of controlling distillation of solid volatile-containing carbonaceous fuel which comprises adding said fuel in admix-

ture with coke to any portion of the upper cross section of a column of the mixture advancing downwardly through a shaft retort, distilling said fuel by passing a hot non-combustion-supporting gas upwardly through the column in direct heat transferring relationship therewith, and removing the gas and volatile products distilled from any portion of the fuel selectively from the top of the shaft so as to force the gas to distribute itself substantially uniformly throughout each cross section of the column during its upward passage therethrough.

5. A method of controlling distillation of solid volatile containing carbonaceous fuel, which comprises adding two or more kinds of said solid fuel simultaneously to separate portions of the upper cross section of a shaft retort, directing the fuel downwardly in separate vertical columns through the shaft and distilling them by direct heat transfer with upwardly flowing currents of hot non-combustion-supporting gas, and removing the volatile products evolved from each fuel separately and selectively from the upper portion of the shaft.

6. A method of controlling distillation of solid volatile-containing carbonaceous fuel which comprises adding two or more kinds of solid fuels simultaneously to separate portions of the upper part of a fuel bed in a shaft retort having a gas outlet near its top, directing the fuels downwardly in vertical columns through the shaft, distilling the volatile-containing fuels by direct heat transfer with an upwardly flowing current of hot non-combustion-supporting gas and causing the gases passing upwardly through the fuel bed to pass transversely of the vertical layers in flowing to said gas outlet near the top of the shaft.

7. A method of controlling distillation of solid volatile-containing carbonaceous fuel which comprises passing a current of hot gases upwardly through a column of the fuel advancing downwardly through a shaft retort and distilling the fuel by heat exchange with said gases, passing the fuel in some portions of the column through the shaft at a faster controlled rate than that in others and adding more fuel to certain portions of the upper cross section of the column than to others.

8. An apparatus for controlling the distillation of solid volatile-containing carbonaceous fuel distilled by direct heat transfer with hot gases, the said apparatus comprising an upright shaft retort, a fuel hopper superimposed thereon having a plurality of charging necks leading from its base into the top of the shaft over substantially the entire upper cross section thereof, a gate in each charging neck for controlling the admission of fuel through each neck into the top of the shaft, a plurality of vertical chambers each

having an open bottom and being suspended in the top of the shaft beneath but in communication with a respective charging neck for directing the fuel in vertical columns in its downward passage through the upper portion of the shaft, and means for flowing distillation vapors at a controlled rate selectively through one or more of the said vertical chambers in a direction countercurrent to the fuel flow therethrough.

9. An apparatus for controlling distillation of solid volatile-containing carbonaceous fuel distilled by direct heat transfer with hot gases comprising an upright shaft retort having a multiple compartment fuel charging box suspended in its top and filling substantially the whole of its upper cross section, a gas offtake conduit leading off from the shaft through each compartment of the charging box, and a valve in each conduit for controlling the volume of gas removed from the shaft through each compartment of the charging box.

10. An apparatus for controlling distillation of solid volatile-containing carbonaceous fuel distilled by direct heat transfer with hot gases comprising an upright shaft retort, a number of chambers of substantially uniform cross section suspended at regular intervals within the top of the shaft and opening into the shaft over substantially its entire upper cross section, a fuel charging neck opening into the top of each chamber, each charging neck having a charging gate for controlling the admission of fuel therethrough, a gas offtake conduit leading off from the top of each chamber, and a valve in each conduit for controlling the selective removal of gas from the top of the shaft through each chamber.

In testimony whereof I affix my signature.
HENRY L. DOHERTY.
